AUTOMATIC FUEL SUPPLY FOR BURNERS

Thomas J. Garrett, Troup, Tex.

Application September 6, 1934, Serial No. 743,001

1 Claim. (Cl. 236—8)

This invention relates to means for supplying fuel to burners and particularly burners used in conjunction with steam boilers.

An object of the invention is to provide means whereby either oil or gas may be supplied to the burner in a substantially automatic manner.

The invention further consists in the provision of an improved means for controlling the supply of fuel to the burner in such a manner to insure against over or under supply of fuel.

The invention, together with its objects and advantages, will be best understood from a study of the following description taken in connection with the accompanying drawings wherein:

Figure 1 is an elevational view of the invention. Figure 2 is a top plan view thereof.

Figure 3 is an elevational view taken at right angles to Figure 1.

Figure 4 is an enlarged sectional view of a needle valve and pressure responsive means associated therewith for controlling the operation of the valve.

Figures 5 and 6 are detail sectional views taken substantially on the lines 5—5 and 6—6, respectively, of Figure 1.

Figure 7 is a detail view of the needle valve.

In accordance with the present invention and as illustrated in the drawings, there are provided two identical devices indicated by the reference numerals 10 and 10a, respectively.

Each of the devices 10 and 10a comprises a vertical frame structure 11 at the upper end of which is a cylinder 12, and at the lower end of which is a cylinder 13. Operating in the cylinder 12 is a piston 14 that is provided with a stem 15 operating through a gland 16 in the bottom of the cylinder 12. Operating in the cylinder 13 is a piston 17 having a stem 18 operating through a gland 19 in the top of the cylinder 13. The ends of the stems 15 and 18 are threaded and at said ends the stems are connected together through the medium of a coupling sleeve 20.

Normally acting to urge the piston 14 upwardly, and also the piston 17 upwardly, is a spring 21 that is disposed about the stems 15 and 18, and engaged with the ends of the spring 21 are adjusting nuts 22 and 23, the former, nut 22, being screw-threadedly engaged with the outer end of the stem 15, and the latter, nut 23, being screw-threaded on the tubular extension 13a of the cylinder 13 as clearly shown in Figure 4. Obviously, through the medium of the nuts 22 and 23, the tension of spring 21 may be regulated as found desirable.

Threaded onto the bottom end of the cylinder

13 is a needle valve casing or block 24 having a tapered passage 25 extending therethrough and in which is adapted to seat a tapered needle valve 26 which, as clearly shown in Figure 7, is threaded onto the inner end of the piston stem or rod 18.

For the upper ends of the cylinders 12 there are provided caps 27 as shown.

A steam line 28 leading from any suitable source of supply is at one end connected with a manifold 29 that in turn is threaded into the caps 27 for supplying steam to the cylinders 12 in a manner to move the pistons 14 downwardly to engage the needle valves 26 with their respective seats 25. For controlling the supply of steam to the cylinders 12 there are provided in the ends of the manifold 29 suitable valves 30.

One of the valve devices, for example, the valve device 10, is adapted to be used for controlling the supply of steam to the burner and in this connection it will be noted that a steam line 31 leading from a suitable source of supply is connected at one end with one side of the valve block or casing 24 of the valve assembly 10 and is in communication with the passage 25 of said valve block.

From the valve block 24 of the valve assembly 10 steam passes to the burner through steam lines 31a and 31b that are connected by piping 32 with said valve block 24 of the assembly 10 at the lower end of the passage 25. In this connection it will be noted that the piping 32 is connected with the steam line 31 through the medium of a by-pass 33. Arranged in the by-pass 33 is a valve 34 while a valve 35 is arranged in the steam line 31 and valves 35a and 35b, respectively, are arranged in the lines 31a and 31b, respectively.

Substantially the same piping arrangement is associated with the valve assembly 10a for feeding oil to the burner, the oil line assembly including an oil pipe or conduit 36 leading from a suitable source of supply and connected at one end with one side of the valve block 24 of the valve assembly 10a. Oil conduits 36a and 36b are connected with the valve block 24 of said assembly 10a through the medium of a piping 37 which latter is connected with the pipe 36 through the medium of a by-pass 38. Arranged in the line 36 is a valve 39 while arranged in the by-pass 38 is a valve 40. Also arranged in the line 36b is a valve 39a.

From the above it will be apparent that when the needle valves 26 are in open position, steam and oil in the proper proportions will be fed to the burner. When the steam generated in the

boiler exceeds a predetermined amount, certain of the steam pressure will be utilized through the medium of the piping 28 for causing the pistons 14 to move downwardly to close the valves 26 thus shutting off, materially, the amount of steam and oil being supplied to the burner. With the valves 26 in closed position, the valves 35 and 39, and also the valves 34 and 40 are opened so that a small amount of steam and oil may be fed to the burner sufficient to maintain a sufficient flame and preventing the fire or burner becoming completely extinguished.

Obviously, when the steam pressure in the boiler falls below a predetermined amount, the pistons 14 will move upwardly under action of the springs 21, thus opening the valves 26 when a greater volume of steam and oil is then permitted to flow to the burner.

It will be thus seen that through the medium of this device the flow of oil or gas and steam to the burner of the boiler will be automatically

controlled and can be regulated as found desirable.

What is claimed is:

A fuel regulator for oil burners comprising, a pair of spaced cylinders, a piston in each cylinder, rods connecting said pistons, an adjusting nut on one of said rods, a coil spring encircling said rods, one end of said spring being adjustable with respect to the end of one of said cylinders the other end of said spring being in abutting relation with said adjusting nut, a steam inlet opening in the upper portion of one of said cylinders for communicating steam into said cylinder above the piston therein, a valve casing secured to the other cylinder having a tapered bore therein, communicating with a pair of spaced passages, and a tapered valve secured to the piston adjacent the valve casing movable in and out of said tapered bore for controlling a flow of fluid through said passages. 10
